ATTORNEY

UNITED STATES PATENT OFFICE.

NICHOLAS LOESEL, OF RICHMOND HILL, NEW YORK, ASSIGNOR TO AMERICAN CAN COMPANY, OF NEW YORK, N. Y., A CORPORATION OF NEW JERSEY.

SEPARATING DEVICE FOR CAN CAPS OR THE LIKE.

Application filed May 13, 1925. Serial No. 29,945.

My invention relates to feeding mechanism for can covers or caps and has for its main object the provision of an apparatus for separating caps or covers of the straight flange type, which have a tendency to nest together and in the past have been found difficult to separate and properly feed in automatic machinery. Caps or covers of this character not only have a tendency to nest together, but assume very irregular arrangement, the flanges on one side of adjacent caps being as likely to be in close contact as those on the other and when in such contact being very hard to separate to remove an individual cap from the stack. This difficulty is aggravated when the caps are of very small diameter, such as those shown on the drawings, which are adapted for use upon olive oil containers and are approximately one inch in diameter.

The apparatus provided by the present invention is constructed and operates in manner to overcome these difficulties, as will hereinafter appear.

Numerous other objects and advantages of the invention will be apparent as it is better understood from the following description, which, taken in connection with the accompanying drawings, discloses a preferred embodiment thereof.

Referring to the drawings,

Figure 1 is a view, partially in section and partially in elevation of an apparatus in which my invention is embodied;

Fig. 2 is an enlarged sectional detail of the arcuate passage through which the caps are directed to separate them in the fan-like arrangement shown; and

Fig. 3 is a front elevation of the apparatus, illustrating the passageway for the caps and the separator slides and actuating mechanism therefor.

On said drawings, illustrating the best manner in which I have thus far contemplated applying the principles of my invention, the reference character 11 indicates a frame, in which is journaled a drive shaft 12, carrying a crank disk 13, connected by means of a link 14 and an arm 15 with a rock shaft 16 also journaled in the frame 11. Said link 14 is formed of yieldingly connected parts comprising a rod 17 and a sleeve 18 into which said rod extends, the latter having thereon a spring 19, compressible between a disk 21 on one end thereof

and a washer 22 near the opposite end. Said rod is connected by a part 23 with said arm 15 and is adapted to be rocked by the mechanism just described, in manner which will be obvious, the power being supplied to the shaft 12 from any suitable source (not shown).

A segmental gear 24 is carried on the shaft 16 and meshes with a rack 25, rigid with a slidable member 26 disposed in a guideway 27 in a front part 28 of the frame to which guide plates 29 are secured by means of screws 31. The rack 25 is secured to said slidable member 26 by means of screws 32 and moves in a slot 33 provided in said front part 28 of the frame. The upper part of said frame is formed to provide an arcuate passage 34 at the base of a stack holder consisting of a plurality of rods 35 screwed into a top plate 36. As the caps descend through the stack holder 35, they are likely to be arranged in the irregular manner referred to above, which is illustrated in Fig. 2 of the drawing. With the flanges arranged in the nested relationship shown, the laterally operating separating devices ordinarily used to separate can covers and the like from a stack or supply chute are not satisfactory, since they do not always enter between the flanges of adjacent covers and more than one, therefore, may be fed at one time, or the action of said devices may be obstructed by a solid line of nested flanges. By means of the arcuate passage 34, covers are conducted from their horizontal position in the vertical chute 35 to vertical position, as shown in Figs. 1 and 2, being separated during this movement and disposed in fan-like formation so that they may be individually separated by beveled cut-out fingers 37 provided on said slidable member 26 near the top thereof. These fingers are arranged to engage the opposite sides of said flanges and as they rise between adjacent covers, the outermost cover is entirely freed from the stack and permitted to fall through a vertical chute provided by the guide plates 29, from which they are delivered into any suitable mechanism, such, for example, as a cap and can assembling mechanism, or soldering machine.

The caps are indicated by the reference character 38 and the straight flanges thereof by the character 39, the latter being retained

behind said guide plates 29 as the caps descend, as shown in Fig. 3. A cross piece 41 is secured by screws 42 to spaced upper portions 43 of the slide 26 and has downwardly extending beveled fingers 44 near the opposite ends thereof, the lower inner edge of said cross piece being also beveled as indicated at 45 in Fig. 2. As the slide ascends, the beveled fingers 37 engage the inner side 10 of the flange 39 of the outermost cap, forcing the latter outwardly and when completely separated, said flange passes down between said fingers 37 and the fingers 44, the body of the cap following the incline 45 on 15 the member 41. Said member 41, in the lower positions of the slide as shown in Figs. 1 and 3, prevents the caps from falling forward and limits the arc through which the upper portions of the flanges 39 pass 20 relative to the arc traversed by the lower portions of said flanges, thus producing the fan-like arrangement of said caps for the purpose hereinbefore stated.

It is thought that the invention and many 25 of its attendant advantages will be understood from the foregoing description, and it will be apparent that various changes may be made in the form, construction and arrangement of the parts without departing 30 from the spirit and scope of the invention, or sacrificing all of its material advantages, the form hereinbefore described being merely a preferred embodiment thereof.

I claim:

1. Apparatus for separating adjacent articles, as straight-flanged container closures or the like, comprising means for receiving the articles from a stack in which they are arranged in a horizontal plane and conducting them to a substantially vertical position with the edges thereof spaced apart to facilitate separation of the articles for individual feeding, and combined therewith means for separating the articles at their spaced-apart 45 portions and for feeding the separated articles.

2. Apparatus for separating adjacent articles, as straight-flanged container closures or the like, comprising means for receiving the articles from a stack in which they are arranged in a horizontal plane and conducting them to a substantially vertical position with the edges thereof spaced apart to facilitate separation of the articles for individual feeding, and a movable member adapted to enter between the most advanced article and the one next thereto to positively separate the same.

3. Apparatus for separating adjacent articles, as straight-flanged container closures or the like, comprising means for receiving the articles from a stack in which they are arranged in a horizontal plane and conducting them to a substantially vertical position 65 with the edges thereof spaced apart to facil-

itate separation of the articles for individual feeding, a movable member adapted to enter between the most advanced article and the one next thereto to positively separate the same, and means providing a discharge passage for the separated articles.

4. Apparatus for separating adjacent articles, as straight-flanged container closures or the like, comprising means for receiving the articles from a stack in which they are arranged in a horizontal plane and conducting them to a substantially vertical position with the edges thereof spaced apart to facilitate separation of the articles for individual feeding, a vertically reciprocable cut-out member provided with means for holding said articles in position for separation, and means for freeing the outermost article from the remainder.

5. Apparatus for separating adjacent articles, as straight-flanged container closures or the like, comprising means for receiving the articles from a stack in which they are arranged in a horizontal plane and conducting them to a substantially vertical plane 90 with the edges thereof spaced apart to facilitate separation of the articles for individual feeding, a vertically reciprocable cut-out member provided with means for holding said articles in position for separation, and means for freeing the outermost article 95 from the remainder and for guiding the same to a point of discharge.

6. Apparatus for separating adjacent articles, comprising a stackholder in which the articles may be arranged irregularly, as with the flanges in nested relation in the case of container closures, means for arranging said articles in fan-like formation with the flanges thereof separated to facilitate individual feeding and a slide movable towards and from the separated parts of said articles and having cut-out means.

7. Apparatus for separating adjacent articles, comprising a stackholder in which the articles may be arranged irregularly, as with the flanges in nested relation in the case of container closures, means providing an arcuate passage for receiving said articles and turning them progressively from horizontal to vertical position, and cut-out means for operating between said arranged articles arranging them in fan-like formation with the flanges thereof separated to facilitate individual feeding.

8. Apparatus for separating adjacent articles, comprising a stackholder, a curved passage at the bottom of said stack holder for turning the articles from horizontal to vertical position and arranging the articles in a formation in which the edges thereof are more widely separated than in the stack to facilitate individual feeding, and cut-out means.

9. Apparatus for separating adjacent ar-

ties, comprising a stack holder, an arcuate passage at the bottom of said stack holder for arranging the articles in a formation in which the edges thereof are more widely separated than in the stack to facilitate individual feeding said passage being open to allow the articles to move to substantially vertical position, a reciprocating cut-out member adapted to enter between the outermost article and the remainder, a rack member rigid with said reciprocating member, a rock shaft, a gear on said rock shaft meshing with said rack, and means for operating said shaft.

15 10. Apparatus for separating adjacent ar-

ties, comprising a stack holder, an arcuate passage at the bottom of said stack holder for arranging the articles in a formation in which the edges thereof are more widely separated than in the stack to facilitate individual feeding, a reciprocating cut-out member adapted to enter between the outermost article and the remainder, a rack member rigid with said reciprocating member, a rock shaft, a gear on said rock shaft meshing with said rack, and means including a yieldable connection for operating said shaft. 20
